CLAIM

The ornamental design for a frame portion for a laundry enclosure panel, as shown and described.

DESCRIPTION

FIG. 1 is a front perspective view showing the frame portion for a laundry enclosure panel of Applicant's invention.

FIG. 2 is a front elevation of the frame portion for a laundry enclosure panel of Applicant's invention.

FIG. 3 is a side elevation of the frame portion for a laundry enclosure panel of Applicant's invention, both sides being identical.

FIG. 4 is a top elevation of the frame portion for a laundry enclosure panel of Applicant's invention; and,

FIG. 5 is a bottom side elevation of the frame portion for a laundry enclosure panel of Applicant's invention, both sides of the case being identical.

The broken line showing is for illustrative purposes only and forms no part of the claimed design.
